UNITED STATES PATENT OFFICE.

CHARLES L. BAENDER, OF OAKLAND, CALIFORNIA, ASSIGNOR, BY MESNE ASSIGNMENTS, TO NATIONAL SWEEPER COMPANY, OF TORRINGTON, CONNECTICUT, A CORPORATION OF NEW JERSEY.

CARPET-SWEEPING APPLIANCE.

1,138,437.

Specification of Letters Patent.

Patented May 4, 1915.

Application filed June 28, 1909. Serial No. 504,878.

To all whom it may concern:

Be it known that I, CHARLES L. BAENDER, a citizen of the United States, and a resident of Oakland, in the county of Alameda and 5 State of California, have invented new and useful Improvements in Carpet-Sweeping Appliances, of which the following is a specification.

This invention relates to a carpet sweeping appliance operating by atmospheric pressure to draw in and gather the dust and "sweepings" from a carpet while the appliance is moved over its surface.

The carpet sweeper of my invention operates on the principle of producing a continuous suction or exhaustion of the air in a closed receptacle sufficiently below the normal pressure of the atmosphere to induce an inflow of air through a slit or nozzle and thereby draw the dust and sweepings into the receptacle as the appliance is moved over the carpet.

The invention embraces the novel construction and combination of a dust receptacle on wheels, suction bellows and means for operating the bellows in such manner as to produce and maintain a continuous suction at the inlet slit in the receptacle as the same is moved over the surface of the carpet.

The invention embraces further a novel means of loosening the pile of the carpet and dislodging the dirt or particles thereon in the region of the suction nozzle.

The nature of the said improvements, and the manner in which I proceed to produce apply and carry out the same are explained at length in the following description, wherein reference is had to the accompanying drawings illustrating a preferred construction of a carpet sweeping appliance embodying the various features of my invention.

Figure 1 of the drawings is a plan or top-view of the carpet sweeper of my invention, in which the air exhausting device is constructed in the form of a pair of bellows. Fig. 2 is a side elevation. Fig. 3 is a longitudinal section. Figs. 4 and 5 are 50 details of the mechanism through which the movements of the sweeper over the carpet are caused to operate the bellows; Fig. 5 being a side-view of one of the wheels, and

Fig. 4 a side-view of the levers through which the cams act on the bellows. Fig. 6 55 is a perspective view, on an enlarged scale, of the air nozzle on the suction receptacle. Fig. 7 is a similar view of the dirt loosening device on the bottom of the dust receptacle.

In the carpet sweeper of my invention an 60 exhaust atmosphere, or a condition below the normal atmospheric pressure outside, is set up in the dust receptacle α through the medium of a pair of suction bellows $b-d$, arranged on the top of the body or 65 casing α' to which the receptacle α is detachably connected. Each bellows consists, besides the casing α' , of a movable top board 2 and a flexible collapsible diaphragm 3 which, as it is alternately expanded and collapsed by reciprocating the top board, acts to draw in the air from the dust receptacle α through ports 4 in the bottom 5 and expel the same through an outlet 6 in the movable top-board. As the two top-boards 2 are moved 75 up and down the bellows are actuated in an alternate manner,—one expanding while the other is collapsing—an exhausted condition of the atmosphere in the dust receptacle is produced that is sufficiently low to set up a 80 current or inflow of atmospheric air through the slit 9 in the nozzle f , and the two bellows $b-d$ being arranged as shown and actuated in an alternate manner will maintain a 85 continuous exhaust in the dust receptacle sufficient for all practical purposes. The number of bellows can be increased, however, when greater power or capacity is desired by providing a longer or a wider casing on which the additional room will accommodate 90 a greater number of bellows than two of the size or power of those illustrated in the drawings.

A further novel feature consists in placing the carrying wheels under the rear end, 95 and supporting the weight of the front end of the cleaner principally by an adjustable shoe placed under the front end behind the suction nozzle, the shoe being adjustable in such manner that the working distance of 100 the bottom face of the suction nozzle from the surface of the carpet can be adjusted thereby causing the bottom face of the nozzle to work in different relation to the carpet, or to touch and bear on the same with 105 greater or less pressure.

The nozzle *f* is formed or provided with a tubular body 10 having a narrow slit or orifice opening into the dust-receptacle *a* through the bottom, and terminating in a 5 relatively broad foot 12, in the middle of which the orifice 9 extends transversely for the entire width of the receptacle.

The handle *k* by means of which the 10 sweeper is propelled and directed over the carpet is attached to the end of the casing nearest the wheels *g*—*h*. The opposite end under which the nozzle is situated, being the front or leading end, is held up by the nozzle, and by its weight also keeps the foot of 15 the nozzle against the surface of the carpet with sufficient pressure to insure a close contact at all times. The surface of the nozzle foot is preferably corrugated or formed with ridges as shown, that it may the better 20 rub up the pile or texture of the surface over which it is drawn and so loosen and dislodge the dust and particles.

In the preferred construction of this nozzle—illustrated in Fig. 6—the tubular body 25 10 is secured to the bottom of the receptacle *a* by a flange 13; the corrugated foot 12 extends beyond the sides as well as in front of and behind the nozzle.

A further novel feature in connection 30 with the dust receptacle consists in dividing it by a partition 14 into a dust collecting compartment *m*, for the larger particles and principal portion of the sweepings, and a pocket *n* in which the finest particles of dust 35 are collected and retained. These compartments *m*—*n* are separated from the bellows *b*—*d* by a screen *p* placed under the ports 4, the interstices or apertures in which are sufficiently fine to prevent the fine dust from 40 being carried out by the air currents, and cause it to drop or precipitate instead into the pocket *n*. The partition 14 forming the bottom of the pocket *n* is set at an angle as shown, for the purpose of causing the particles thrown down by the screen to collect 45 in the corner and deepest part of the pocket farthest from the nozzle and thus be cut off from, or kept out of the direct line of, the inflowing air currents.

50 For convenience in cleaning out the dust receptacle, the Partition 14 is removably fixed in place by brackets 15 on the sides of the receptacle. The receptacle itself is also detachably fastened on the body or casing 55 carrying the suction apparatus and its actuating mechanism; being secured to the casing by clasps or catches of any well known form or character, such as are used to fasten the lid of a box or a trunk to the body.

60 As embodied in the present construction, the revolving motion of the wheels *g*—*h* produced by contact with the carpet is converted into the necessary reciprocating motion of the bellows by means of face cams 65 fixed on the wheel axles, and a system of

rocking levers and rock-shafts for each bellows; the mechanism being properly timed and arranged to operate two bellows in such manner that as one approaches the end of its stroke but before its action on the enclosed space in the receptacle ceases, the other bellows begins to exhaust, and the suction or exhaustion becomes practically continuous. To effect this operation from the rotation of the axle the cams *s*—*t* clutched to 70 the axle 16 are arranged in such relation to each other and are so designed that one or the other of the levers 18—19 fulcrumed on the bottom of the body is always riding upward on the cam face. The cams *s*—*t* are 75 placed at such distance apart that the levers 18—19 may lie between them and allow the rollers 26—27 to engage the cam face.

The lever 18 actuates the rock-shaft 20 from which the movable board of the bellows *b* nearest the rear end of the casing gets its motions, and the outer end of that lever is connected with an arm 21 on the end of the rock-shaft 20 by the connecting rod 24. The lever 19 is similarly connected with the rock-shaft 36 of the bellows *d* nearest the front by the arm 22 fast on the rock-shaft, and the connecting rod 23. Both levers 18—19 are pivotally attached at the ends to a common bracket 25 on the bottom of the casing. 95

A roller stud 26 on the lever 18 rests on and is held in working contact with the face of the cam *s* by a curved switch-piece *v*, and the roller stud 27 on the lever 19 engages in like manner the cam *t*. The relative positions of the cam *t* and the lever 19 are shown in Fig. 4, where the cam is indicated by dotted lines; it being situated on the side of the wheel *h* which would lie in front of the wheel *g*, and consequently cover the 100 wheel *g* and cam *s* if it were included in Fig. 4. The cams *s*—*t* being set in opposite relation, it will be obvious that the levers 18—19 will move in contrary direction, or one following the other, in such time that one bellows will take in air while the other is expelling, and thereby produce a continuous 105 and not an intermittent exhaustion of air from the dust receptacle.

The wheels are loose on their axles and 110 are separately connected each by a friction clutch so arranged that the wheels will engage only in the forward travel or movement of the sweeper and the appliance can be handled and operated like an ordinary 120 brush carpet-sweeper with a forward and backward movement; which has the advantage of causing the nozzle to loosen and dislodge the dust and dirt and any particles adhering to the pile of the carpet and thus be 125 readily taken up by the suction as the nozzle moves over them.

The clutch employed in the present construction consists of a notched disk 28 fast on the axle, a circular flange 29 on the side 130

of the wheel surrounding the disk 28, and friction dogs in the form of rollers 30 lying loosely in the recesses between the eccentric faces of the flange; the recesses being of such form that the dogs 30 will bite on the flange when the wheel is turning forward; but will not engage the flange in the reverse direction of travel.

A further novel feature consists in a dirt 10 loosening shoe of peculiar construction and arrangement behind the suction nozzle *f*. As herein embodied the device is in the form of a shoe or corrugated plate 35, as seen in Fig. 7, the rear edge thereof being connected to the bottom of the dust receptacle in the rear of the suction nozzle, but adjustably attached thereto at the front edge, by a cranked rod 31 from hangers 32 on the sides of the casing. One end of the crank-rod terminates in a handle 33 on the outside of the hanger 32, and, by means of stop-pins 34 on the side of the casing, the handle may be locked or fixed in any one of several angular positions, the effect of which is to raise 20 or lower the shoe at the front side. By this adjustment the contact of the bottom of the nozzle with the carpet is regulated, with the effect to cause the nozzle to bear with varying degrees of pressure on the carpet under 25 the weight of the cleaner, or to work in any desired relation to the surface of the carpet, or with little or no pressure. As thus arranged, it will be obvious that the weight of the load at the front end can be thrown 30 either entirely on the suction nozzle, or partly on the suction nozzle and shoe 35, and the working relation of the suction nozzle can be nicely regulated, simply by adjusting the shoe, for which provision is made as before described. This adjustment is made 35 from the front end, the opposite end being attached to the bottom of the receptacle by hangers, as seen in Figs. 2, 3 and 7.

It will be observed that the screen *p* is secured to the bottom edge of a wall *q* depending from the bottom of the casing around the valve openings 4, said wall *q* depending into said dust receptacle *m*. This screen *p*, serving as it does to separate the dust from 40 the air, offers considerable resistance to the action of either suction bellows, and, consequently, when either suction bellows is operating, and the corresponding valve 4 is open, there is a current of air through substantially the whole surface of the screen *p*. But it is necessary, for this result to take 45 place, that the screen *p* be spaced, as shown, by means of the wall *q*, from the valve openings 4. The arrangement of the screen *p* with reference to the valve openings and the suction bellows constitutes an important feature of my invention, as it not only serves to 50 separate the dust from the air passing through said bellows, which result has been attained in prior devices, but, by its loca-

tion between the nozzle and the valve openings, and on account of its being spaced from said valve openings, it serves to equalize the suction through all parts of said screen, thereby rendering said screen less liable to 70 be choked up with dust and more effective in operation.

I claim:—

1. The combination in a pneumatic carpet cleaner, of a casing, a dust box, a screen 75 device in the upper portion of said box removable therefrom, a suction nozzle secured to and supporting the front end of said cleaner, the exit thereof entering said box under the screen device, a suction device 80 above the box communicating with the interior thereof above the screen device, journal bearings on the casing in rear of the box, a shaft supported in said bearings, traction wheels on said shaft adapted to support the 85 rear end of the cleaner and cam and lever connections between the shaft and the suction device for operating the latter.

2. The combination in a pneumatic cleaner / having traction wheels supporting the rear 90 thereof, a dust receptacle removable from the cleaner and having a horizontal screen device in its upper portion, a suction nozzle supporting the front end of the receptacle, the exit from the nozzle entering the receptacle below the screen device, a suction device above the receptacle and connecting devices between the wheels and the suction device for operating the latter.

3. The combination in a pneumatic carpet 100 cleaner, of a dust box, a screen device removably mounted on the upper portion of said box adapted to be removed and replaced in said box, a suction nozzle secured to and supported in the front end of said box, the 105 exit therefrom entering said box under the screen device, journal bearings secured to the machine in rear of said box, a shaft in said bearings, a suction device above said box communicating with the interior thereof above said screen device, traction wheels secured on the shaft adapted to support the rear end of the cleaner and rotate the shaft, and connections between the shaft and the 110 suction device for operating the latter. 115

4. In a sweeping appliance, the combination of a dust receptacle, a nozzle communicating therewith and supporting the front end thereof, a suction device over said receptacle and communicating therewith, 120 screening means located between the nozzle and suction device, wheels forming the rear support of said appliance, and operative connections between the wheels and the suction device adapted to operate said device upon 125 the rotation of the wheels.

5. In a sweeping appliance, the combination of a dust receptacle, a nozzle supporting the front end thereof and communicating therewith, wheels located near the rear 130

end of said dust receptacle, a suction device located over said dust receptacle and communicating therewith through valve-controlled apertures, a wall removably supported in the receptacle around said apertures, a screen secured to the periphery of said wall, operative connections between said

wheels and said suction device for operating said device upon the rotation of said wheels.

CHARLES L. BAENDER.
